UNITED STATES PATENT OFFICE.

CHARLES WHITTAKER, OF MILWAUKEE, WISCONSIN.

IMPROVEMENT IN HAT-RACK AND SEAT COMBINED.

Specification forming part of Letters Patent No. **186,648**, dated January 23, 1877; application filed November 27; 1876.

To all whom it may concern:

Be it known that I, CHARLES WHITTAKER, of the city of Milwaukee, in the county of Milwaukee and State of Wisconsin, have invented certain new and useful Improvements in Hat-Rack and Seat Combined; and I do hereby declare that the following is a full, clear, and exact description thereof, which will enable others skilled in the art to which it appertains to make and use the same, reference being had to the accompanying drawings, and to letters of reference marked thereon, which form a part of this specification.

The object of my invention is to provide a suitable and convenient rack for hats, in combination with a seat such as are commonly used in theaters, opera-houses, &c.

Figure 1 represents a perspective view of my invention, the seat A being thrown back, preparatory to inserting the hat between the arms B of the rack.

The hat-rack C is made of sheet metal or its equivalent, and may be "struck up" or

pressed from one piece of metal, no seam being necessary in its construction. D are screws by which the rack C is attached to the bottom of the seat. F is a flange, which affords protection to the hat from behind the seat.

When the hat is inserted between the arms B the seat is thrown forward, and the hat is suspended by its rim upon the arms B.

I do not claim as my invention the peculiar form of the arms B, any other form to please the taste may be substituted for it.

I claim as my invention, and desire to secure by Letters Patent—

The combination of the hat-rack C, having arms B, and guard F, with the chair-seat A, substantially as described.

In testimony that I claim the foregoing as my own I affix my signature in presence of two witnesses.

CHARLES WHITTAKER.

Witnesses:

MARY WHITTAKER,
K. SHAWVAN.
